UNITED STATES PATENT OFFICE.

ERNEST A. LE SUEUR, OF OTTAWA, ONTARIO, CANADA.

ELECTROLYTIC CELL.

1,359,716.

Specification of Letters Patent. Patented Nov. 23, 1920.

Application filed May 13, 1918. Serial No. 234,296.

To all whom it may concern:

Be it known that I, ERNEST A. LE SUEUR, a citizen of the Dominion of Canada, residing at Ottawa, in the county of Carleton and Province of Ontario, Canada, have invented new and useful Improvements in Electrolytic Cells, of which the following is a specification.

My invention has special reference to single liquid simple electrolytic cells having carbon anodes and is adapted to utilizing the carbon plates of the limited sizes obtainable in commerce so as to build up and effectively supply with heavy currents, with a maximum of simplicity and minimum of expense, great electrode areas.

In the drawings illustrating my invention, Figure 1 is a side elevation of a cell, the containing vessel being in vertical central section.

Fig. 2 is plan of the same.

Fig. 3 is an end elevation of said cell showing all the containing vessel broken away except the bottom.

Fig. 4 is a detail of a cathode section.

Fig. 5 is a detail of a bolt with accessories.

Fig. 6 shows a duplex form of current leading in member.

Fig. 7 shows an alternative method of connecting the anodic plate surfaces.

Figs. 8 and 9 show a composite anode having an alternative arrangement of current leading in members.

In said drawings, 1 is a current leading in member, preferably of carbon, formed, in the case shown, of a round piece flattened on two opposite sides near its lower extremity; 2, 2 and 2', 2' are separate divisions of composite carbon plate surfaces; said divisions are shown of different widths and separated by a gap, but neither of these conditions is essential; 3, 3 are blocks, preferably of carbon, separating mechanically

and connecting electrically the several pieces 2 and 2' with the current leading in member 1; 4, 4 are plates, preferably of metal, as steel, constituting sections of the total cathode surface; 5, 5 are insulating pieces, conveniently of slate, hard rubber or the like; 6, 6 are plates, preferably of metal, as steel; 7 is a bolt, insulated from the carbon parts

by the pieces 5, 5 and the insulating sleeve 71, Fig. 5, and binding said parts together; 72 is a nut on said bolt; said bolt is electrically connected with the negative terminal by the wire 73; 8, 8 are insulating pieces, as of glass, slate or the like, lying on the bottom of the containing vessel 9; said pieces may be of any shape, extent or number desired consistent with the functions they are to fulfil; 9 is the containing vessel which I prefer to make of metal, as steel, 91 is the negative lead fast to said vessel 9 and electrically connected therewith; 10, 10, Fig. 2 are insulating pieces of any convenient form between the pieces 2 and 4; illustration of these is omitted in Fig. 1 to avoid complication of detail; 11 is the electrolyte; 12 is a layer of paraffin wax covering the latter; 21 is a hole in said wax; A is a hole in the member 1 accommodating the insulating bolt 7.

Fig. 6 illustrates a composite carbon current leading in member and attachments. In this figure 1', 1' are the two sections of said member, 2'' and 2''' fulfil similar functions to the parts 2 and 2' in the previous figures; 5', 5'; 6', 6'; and 7', 7' fulfil similar functions to 5, 6 and 7 in the earlier figures.

In Fig. 7, which illustrates a different method of attaching the carbon plate surfaces, the parts 1_a, 2_a, 2'_a, 5_a, 6_a and 7_a correspond in functions with the parts 1, 2, 2', 5, 6 and 7 in the earlier figures. In this figure the current leading in member is shown square.

In Figs. 8 and 9 six (square) current leading in members are shown instead of but one (round) one as in Figs. 1, 2 and 3; also the carbon plate surfaces are shown single piece instead of composite. 1_b, 2_b, 3_b, 5_b, 6_b and 7_b correspond in functions with 1, 2, 3, 5, 6 and 7.

In the cell illustrated the cathode sections receive their current simply by resting on the metallic bottom of the containing vessel. If the latter is not of metal the same method of current supply may be had by using a plate similar to what is shown of the part 9 in Fig. 3, or metallic strips, supplied with cathodic current, underlying the contact portions of the cathode sections.

The insulating pieces 8 are adapted not only as a support for the pieces 2' but as a guard against short circuit in case any of said latter pieces break. Otherwise, support off 5 the bottom may be had in other ways, as by an insulating block (as of cement or brick) beneath the piece 1. The cathode sections may be of any desired shapes and supplied, in any way other than that described, with 10 current; but the great advantages in the matters of cheapness and simplicity incident to the use of this type of free, independent, removable plate connected through simple gravity contact with a metallic bottom 15 will be obvious, and such use is, I believe, novel.

The bolt 7 may be replaced by other equivalent arrangements, as, for instance, by a pair of balanced bolts, properly insulated 20 as is 7, bearing at the points X, X, Fig. 3. For many reasons I prefer the bolting arrangement as illustrated in Figs. 1, 2 and 3. Said bolt may be made of insulating material but at a sacrifice of strength, cheapness 25 and reliability. If no gap is used between the plates 2 and 2' (as in the case of the pieces 2'' and 2''', Fig. 6) or in case the carbon plate surfaces are made single piece instead of composite (as in the case of 30 2_b in Fig. 8) the necessary holes are made to accommodate the bolt 7 and its shield 71. An important feature of my invention is the connecting of said bolt with cathodic current whereby it is protected from attack by the 35 corrosive solutions usually produced in the single liquid type of commercial cell; and the incorporation of a metal bolt in a carbon anode beneath the surface of the electrolyte and exposed to contact with the latter I 40 believe to be novel.

I have shown and described what I consider far the best method for applying the cathode sections, but any other may be used without departing from the other novel 45 points of my invention. More cathode sections than I have shown may be used, especially in the spaces partially occupied by the current leading in members and outside the ends of the carbon plate series. As regards 50 the latter, however, and in spite of the higher electrical resistance involved in the current's flowing between the outer faces of such end plates to the metallic containing vessel 9 compared with what would be the 55 case if cathode sections were supplied at points closer, I prefer not to supply such sections on account of the better protection afforded to those portions of said vessel which would otherwise have cathode sections 60 interposed between them and an anode surface.

Variations in the precise designs illustrated may obviously be made without departing from the essentials of my invention.

65 For one thing, the functions of current lead-

ing in member and carbon separating blocks may be combined and in consequence a multiplicity of narrow current leading in members be employed, each taking its appropriate fraction of the total current from suitable connections above the electrolyte. 70

The general system illustrated herein for building up the composite anode is obviously that of bridging clamps,—the pieces 75 3 and 5 bridging two sections of a composite carbon member (save in case the latter is made single instead of composite) no attempt being made to clamp more than two sections with a single such piece, whereby positive electrical contact is insured between 80 each bridging piece and both sections of the adjacent carbon member. This method is desirable if we are to be able to use the more or less warped and uneven rough plates and other shapes of carbon and 85 graphitized carbon found in commerce without fitting and planing and at the same time secure good contacts. I do not wish to confine myself to the use of plane carbon surfaces for what I designate, for the sake of 90 simplicity, the "plates" and "composite plates" in my apparatus. A special feature of my invention is that it enables me to clamp curved surfaces in pairs according to the principle I have set forth above, and 95 even round carbon rods may be thus treated.

The present invention is especially adapted to the manufacture of hypochlorite bleaching solutions although it may also be employed for other purposes requiring apparatus of this general type. For the (commercially) efficient preparation of sodium hypochlorite a solution of common salt of a concentration of about 45 grams per liter may be used and the temperature be kept 100 relatively low, preferably below 30° C. A good commercial current density is around 30 amperes per square foot of anode surface, and these conditions being fulfilled the depreciation costs on the apparatus are 110 much the lowest of any of which I have known and the production efficiency remarkably high.

The arranging of the member 1 to extend only part way down the face of the plate 2' 115 has the double advantage of economizing carbon and of increasing the area of composite anode that can be made using sizes of carbon current leading members obtainable in commerce.

For the manufacture of most of the products for which the present cell is adapted it is desirable to keep the temperature below the melting point of high grade paraffin wax, and the use of a solid covering of 125 paraffin, as 12, is of great value in suppressing liberation of toxic gas and enhancing the electrochemical efficiency.

I claim:—

1. An electrolytic cell having an anode 130

- possessing a carbon current leading in member and a plurality of composite carbon plates separated by said member.
2. An electrolytic cell having an anode 5 possessing a current leading in member, carbon plates connected with opposite sides of the lower portion of said member, conducting pieces clamped against the outsides of said plates so as to press said plates 10 against said member and a second set of plates clamped against the outsides of said pieces.
3. An electrolytic cell having an anode possessing a composite carbon plate, a plurality of sections of which lie in substantially the same plane, and a carbon member 15 bridging and overlapping in both directions the path of separation of two such sections and clamped against said sections.
4. An electrolytic cell having an anode possessing a current leading in member, two sections of a laterally extending composite carbon plate lying one above another clamped against said member, a separating 20 conducting piece clamped against said composite plate and a second composite plate clamped against the other side of said piece.
5. An electrolytic cell having an anode possessing a current leading in member and 25 paired sections of laterally extending composite carbon plates fast to opposite faces of said member.
6. An electrolytic cell having an anode 30 possessing a carbon current leading in member, a carbon plate extending laterally and downwardly beyond the lower portion of said member, a carbon piece clamped against said plate on the opposite side from said member and another laterally extending carbon plate clamped against said piece on the 35 opposite side of same from the said first mentioned plate.
7. An electrolytic cell having an anode 40 possessing a carbon current leading in member, a carbon plate extending laterally and downwardly beyond the lower portion of said member, a second carbon plate, extending laterally from said member, lying above said first mentioned plate and substantially 45 in the same plane, the said first mentioned plate being of greater width (vertical measure) than the second.
8. An electrolytic cell having an anode 50 possessing a carbon current leading in member, of substantially cylindrical shape at its upper portion and flattened on opposite sides at its lower portion, and carbon plates 55 clamped against said opposite sides.
9. In an electrolytic cell a composite member having carbon anodic parts and metallic cathodic clamping parts insulated therefrom.
10. An electrolytic cell having an anode 60 possessing one or more carbon current leading in members and a plurality of carbon plates, the whole clamped together with 65 metal insulated from said anode and supplied with cathodic current.
11. An electrolytic cell having an anode 70 possessing one or more carbon current leading in members and a plurality of carbon plates bolted together with a metal bolt insulated from said anode and supplied with cathodic current.
12. In an electrolytic cell a plurality of carbon anode surfaces, independent, removable cathode members therebetween, a cathode surface thereunder, contact between the former and the latter cathode surfaces being had by gravity. 75
13. An electrolytic cell having a plurality 80 of carbon anode members, independent, removable cathode members therebetween, a cathode surface thereunder, insulating members preventing contact between said respective anode and cathode members, contact between the former and latter cathode surfaces being had by gravity. 85
14. An electrolytic cell having a plurality 90 of anode members, independent cathode members therebetween, a cathode surface thereunder, insulation partially covering the latter, contact being had between the said cathode members and exposed portions of said cathode surface.
15. An electrolytic cell having a plurality 95 of anode members, independent cathode members therebetween, a cathode surface thereunder, insulation partly covering the latter, contact being had by gravity between said cathode members and exposed portions 100 of said cathode surface.
16. An electrolytic cell having a plurality 105 of carbon anode members, independent cathode members therebetween, a cathode surface thereunder, insulation partially covering the latter surface, electrical contact being had by gravity between said cathode members and exposed portions of said cathode surface.
17. An electrolytic cell having a plurality 110 of anode surfaces, cathode surfaces therebetween, the whole contained in a cathodic metallic tank, insulation partly covering the bottom of said tank beneath said anode and cathode surfaces, electrical contact being had 115 between said cathode surfaces and exposed portions of said bottom.
18. An electrolytic cell having a plurality 120 of anode surfaces, cathode surfaces therebetween, the whole contained in a cathodic metallic tank, insulation partly covering the bottom of said tank beneath said anode and cathode surfaces, electrical contact being had by gravity between said cathode surfaces and exposed portions of said bottom.
19. An electrolytic cell having a covering 125 of paraffin wax floating on the electrolyte.
20. An electrolytic cell having a covering of solid paraffin wax on the electrolyte.
21. An electrolytic cell having a plurality 130

of anode members, cathode members therebetween, a cathode member thereunder and insulation beneath said anode members.

22. An electrolytic cell having a plurality of carbon anode members, cathode members therebetween, a cathode member thereunder and insulation beneath said anode members.

23. An electrolytic cell having a plurality of anode members, cathode members therebetween, a cathode surface thereunder, insulating members between said anode and cathode members and insulation beneath said anode members. 10

ERNEST A. LE SUEUR.
